MANOMETER-PUMPING BALL UNIT FOR A BLOOD PRESSURE GAUGE

Blasius Speidel, Jungingen/Hohenzollern, Germany, assignor to Speidel & Keller KG, Jungingen/Hohenzollern, Germany

Filed Nov. 3, 1971, Ser. No. 195,538

Claims priority, application Germany May 4, 1971

Term of patent 14 years

Int. Cl. D24—02

U.S. Cl. D83—12 R

FIG. 1 is a side perspective of a manometer-pumping ball unit for a blood pressure gauge showing my new design;

FIG. 2 is a front perspective view thereof; and

FIG. 3 is a front perspective as seen from an alternate position.

I claim:

The ornamental design for a manometer-pumping ball unit for a blood pressure gauge, as shown and described.
